UNITED STATES PATENT OFFICE.

OTIS F. PRESBREY, OF BROOKLYN, NEW YORK.

GRINDING MACHINE.

Application filed October 27, 1921. Serial No. 510,792.

To all whom it may concern:

Be it known that I, OTIS F. PRESBREY, a citizen of the United States, and a resident of Brooklyn, in the county of Kings and 5 State of New York, have invented certain new and useful Improvements in Grinding Machines, of which the following is a specification.

The invention relates to a novel grinding 10 machine which has been designed more particularly for grinding the face of the mushroom-head poppet-valves commonly used in internal combustion engines, although it is to be understood that the machine of my 15 invention is not limited in every instance to specific use for grinding the valves of internal combustion engines. The face of a poppet-valve lies at a forty-five degree angle to the axial center line of the valve and it 20 is necessary in the grinding of the valve to maintain the face at this angle. My present invention has been designed to assure the correct grinding of the face of poppet valves and to do this work in an expeditious 25 manner.

The object of my invention is to provide a comparatively inexpensive, simple and durable grinding machine having the adjustments hereinafter mentioned and capable of efficient use.

The invention will be fully understood from the detailed description hereinafter presented, reference being had to the accompanying drawings, in which:

Fig. 1 is a plan view, partly broken away, of a grinding machine constructed in accordance with and embodying the invention;

Fig. 2 is a front view, partly broken away, 40 of the same;

Fig. 3 is a vertical section through a portion of the same, taken on the dotted line 3-3 of Fig. 1, and

Fig. 4 is a vertical section through a portion of the same, taken on the dotted line 45 4-4 of Fig. 1.

In the drawings, 10 designates the supporting bed for the operative features of the machine, this bed preferably being in 50 one integral casting with leg members 11 and of any convenient or suitable outline and proportions.

Upon the bed 10 and preferably integral therewith is a standard 12, in the upper end

of which is secured, by means of a screw 55 13, a stationary axle or cylindrical rod 14 which projects toward the front of the machine and has mounted thereon a rotary tubular shaft 15. Upon the shaft 15 is mounted the grinding wheel 16, a pulley wheel 17, clamping disks 18 engaging opposite faces of said grinding wheel and a shipper hub or disk 19, said disk 19 being a clamping-nut screwed upon the threaded forward portion of the shaft 15 and serving, as one purpose, as a nut for binding the disks 18, grinding wheel 16 and pulley-wheel 17 together upon the inner non-threaded portion of said shaft 15. The shaft 15 is slideable upon the axle 14 so as to permit the grinding wheel 16 to be adjusted toward and from or along the work, and as means for adjusting the shaft 15 and grinding wheel 16 along the axle 14, I provide a shipper-frame 20 having upper 65 70 and lower arms 21 carrying pins 22 within an annular groove 23 formed in the hub or disk 19 and which frame 20 is pivotally mounted by means of a screw 24 on the upper end of a standard 25 projecting upwardly from the bed-plate 10. The frame 20 is formed integrally with a handle or lever 26 by means of which said frame may be given a pivotal action on the upper end 75 80 of the standard 25 and operate through the pins 22 and disk 19 to shift or adjust the tubular shaft 15 forwardly or rearwardly, with the parts carried thereby, on the axle 14. I preferably close the outer end of the 85 90 tubular shaft 15 by means of a threaded cap 27; the pulley-wheel 17 on the inner end of said shaft 15 is fixed to the shaft and imparts rotary motion thereto

At the rear of the grinding wheel 16 are standards 28, 29 connected together at their upper ends by a cylindrical frame 30 which is hollow and provides bearings 31 for a tubular shaft 32 carrying a pulley-wheel 33 and chuck 34 for the stem of the valve 45 intended to be subjected to the action of the grinding wheel 16. The tubular shaft 32 and chuck 34 are arranged at an angle of forty-five degrees to the grinding wheel 16, and this is for the purpose of so holding the valve that its face may be ground at an angle of forty-five degrees with the use of the wheel 16. The chuck 34 is not shown in detail, since it is a well known form of spring 100 105

self-closing chuck of the type shown in Letters Patent of the United States No. 1,104,255, dated July 21, 1914, to George W. Emrick, or No. 1,030,988, granted July 2, 1912, to George W. Emrick. The chuck 34 and tubular shaft 32 receive the stem of the valve 35 and said chuck tightly grips said stem, leaving the valve proper exposed for subjection to the action of the grinding wheel 16. In my construction I provide for the adjustment or movement of the chuck 34, wheel 33 and tubular shaft 32 longitudinally within the bearings 31, said parts being connected together by the fact that the 10 chuck and wheel are screw threaded upon the projecting end of said shaft 32, and as means for adjusting the shaft 32 and parts carried thereby on the longitudinal line of said shaft and along the line of a forty-five 15 degree angle to the grinding wheel 16, I provide the wheel 33 with a grooved hub 35 and engage the same with a pivoted shipper lever 36 operable by means of a handle rod 37. On the movement of the lever 36 from 20 the rod 37, the pulley-wheel 33 and parts connected therewith may be slid in a direction from or toward the standard 29, the wheel 33 being shown in Fig. 4 in its extreme outer adjustment in a direction from 25 the standard 29.

The means for driving the grinding wheel 16 and pulley-wheel 33 and through said pulley-wheel the chuck 34, shaft 32 and the work carried by said chuck, comprises an 30 electric motor 38 mounted below the bed 10 and provided with a drum 39 and a pulley-wheel 40. Upon the drum 39 is a cord or belt engaging the pulley-wheel 17 and said drum and belt impart rotary motion to said 35 pulley-wheel 17 and to the grinding wheel 16. A cord or belt extending from the pulley-wheel 40 to the pulley-wheel 33 serves as means for driving said wheel 33 and the parts connected therewith, and said belt will 40 be twisted around an idler 41 so as to impart movement in the correct direction to said wheel 33.

When the valve 45 is held by the chuck 34, the face of the valve to be ground is 45 exposed and held parallel with the peripheral face of the grinding wheel 16. The grinding wheel 16 may, by means of the lever 26 and its connections, be, while in rotation, slid or adjusted along the face of 50 the valve 45 and be relied upon to truly grind said face even after the peripheral face of the grinding wheel may have become worn, since the grinding wheel may be made to travel toward and from the chuck 55 34 and always evenly grind the face of the valve presented to it. When the valve is 60 first introduced to the chuck 34, said chuck may be in the position in which it is shown in Figs. 1 and 4, and thereupon the chuck 65 may be moved rearwardly by means of the

shipper lever 36 to bring the face of the valve into proper position to be engaged by the peripheral face of the grinding wheel 16, and during the grinding operation the wheel 16 may be adjusted forwardly or backwardly 70 along the face of the valve so as to efficiently and accurately grind the same. The machine of my invention provides two important adjustments, one being the adjustment of the grinding wheel and the other the adjustment of the chuck holding the valve or work, these two adjustments being of importance in securing rapid and efficient duty. The two adjustments referred to may be made, either or both of them, while the machine is 80 in operation, the rotation of the wheel and the rotation of the chuck not in any manner interfering with the adjustment of said parts. The movement of the chuck 34 serves to correctly present the face of the valve to the 85 grinding wheel and the adjustment of the grinding wheel cooperates with that of the chuck in bringing the working face of the grinding wheel against the face of the valve to be ground. The movement of the grinding 90 wheel along the face of the valve is important in not only assuring the correct grinding of the valve, but in adapting the machine for valves varying in dimensions, in which respect, also, the adjustment of 95 the chuck 34 is important.

The machine as a whole has been designed with the view of producing a machine of comparatively inexpensive construction and one in which the operative parts are exposed 100 for observation and any necessary repair. The grinding of the valves is subject to the hand manipulation of the levers 26, 37, and hence the operator may at all times control the action of the machine with respect to the 105 face of the valve.

What I claim as my invention and desire to secure by Letters-Patent, is:

The grinding machine hereinbefore described comprising a supporting bed plate, 110 a rotary grinding wheel mounted thereon, means for manually moving said wheel during the rotation thereof along the line of its axis, a rotary self-closing chuck mounted on a tubular shaft at an angle to the peripheral 115 face of said wheel and adapted to hold the work for presentation to said face, means for manually moving said chuck and its shaft along the line of the longitudinal axis thereof, and means for rotating said grinding 120 wheel and chuck, the means for mounting said grinding wheel being a stationary axle held in a standard extending upwardly from said bed-plate and a tubular shaft mounted on said axle and upon which said 125 grinding wheel, a pulley wheel and a threaded hub are secured in unitary relation so as to be bodily movable along and on said axle, the means for shifting said grinding wheel along the line of its axis consisting of a 130

shipper frame pivotally mounted on a stand-
ard extending upwardly from said bed-plate
and having arms engaging said hub and a
lever for manually moving said frame on its
5 pivotal support, and the means for rotating
said grinding wheel and chuck being an
electric motor having a belt connection with

said pulley wheel and a belt connection with
a pulley wheel on the tubular shaft of said
chuck.

Signed at New York city, in the county of
New York and State of New York, this 21st
day of October, A. D. 1921.

OTIS F. PRESBREY.
